UNITED STATES PATENT OFFICE.

EDWIN G. MASTERS, OF ANDERSON, INDIANA.

NOVELTY DEVICE.

Application filed May 5, 1926. Serial No. 106,974.

The present invention relates to a novelty device which embodies such features of utility, enabling the same to be used as a plumb, level, square, rule, as a gauge, tally, 5 spinwheel, and the like, and which also presents different color schemes.

An important object of the invention is to provide a novelty device of this nature which is exceedingly simple in its construction, inexpensive to manufacture, light, compact, convenient, easy to assemble and disassemble, and otherwise well adapted to the purpose for which it is designed.

With the above and numerous other 15 objects in view as will appear as the description proceeds, the invention resides in certain novel features of construction, and in the combination and arrangement of parts as will be hereinafter more fully described and 20 claimed.

In the drawing:

Figure 1 is a front elevation of the novel device embodying the features of my invention,

25 Fig. 2 is a rear elevation thereof,

Fig. 3 is a sectional view taken substantially on the line 3—3 of Fig. 1, looking in the direction of the arrow,

30 Fig. 4 is an enlarged detail section taken substantially on the line 4—4 of Fig. 3.

Referring to the drawing in detail, it will be seen that 5 designates a back plate having marginal flanges 6 extending right angularly therefrom, and terminating in inwardly disposed extension 7. A square frame 8 is 35 positioned within the flange 6 and holds in place a panel 9. A transparency 10 is positioned between the frame 8 and the inwardly disposed extension 7 of the back plate 5.

40 A pin 11 has its pointed end 12 projecting into a recess 14 provided at the center of the plate 5 and also pierces an opening in the panel 9. This pin 11 is held in place by the transparency 10. An indicator arm 16 45 has one end terminating in a point 17, while the other end merges into an isosceles triangular shaped portion 18. The indicator arm and the portion 18 are constructed of celluloid or any other suitable transparent 50 material.

This indicating device is rotatable on the pin 11 at the juncture of the arm 16 with the portion 18. The three apices of the portion 18 are colored as is indicated to 55 advantage in the drawing, and three areas on the panel 9 are also colored as is indicated

to advantage in Fig. 1, for cooperating with the transparent colors on the portion 18. The panel is further provided with indicia 19 cooperating with which is the arm 16, 60 and the three apices of the portion 18.

A cap 20 has its flange 21 telescopically associated with the flange 6 for the purpose of being associated as is shown in Fig. 3, or the cap may be turned around so as to close 65 over the transparency 10. A thumb tack 23 has its head disposed between the cap 20 and the plate 5, so that the device may be spun thereon to provide a wheel. The rear surface of the back plate 5 has indicia arranged 70 on two edges thereof as is indicated at 25 for the purpose of forming a square. Suitable advertising matter may be placed on this panel plate 5.

This invention is capable of numerous 75 uses such a square and measure, in view of the illustration in Figure 2, the edges of the casing being squared and provided with the major divisions for this purpose. It may be used as a level or plumb with the aid of 80 the indicator 16, by placing the casing in a vertical position as shown in Figure 1 and placing the edge portion thereof against the part of which the level is desired. The indicator will remain in a vertical position, 85 through the action of gravity, while the casing will take the position of the surface to which it is applied and indicate the level or incline of the surface whether it be vertically or horizontally arranged.

90 When using the device as a tally or spin wheel or the like, the device may be laid on a flat surface in a horizontal position and the casing 1 which will provide movement relative to the indicator although it will have a 95 tendency to move in the same direction for cooperation with one or more scale indications on the circumferences provided on the base plate to give a tally for playing games and the like. The cover 5 is also adapted to 100 be mounted over the back of the casing and receives a thumb tack in such a manner that the thumb tack may be applied to the wall and the casing rotated on the thumb tack, the indicator being retained in the vertical 105 position by the action of gravity so that the device will form a sort of roulette wheel for use where it is desired to play any suitable game of chance requiring such an indicator. The device also forms an advertising novelty of considerable value, in view of the 110 fact that the area enclosed within the cir-

circumference provided with the scale divisions 19 is partially obscured by the portion 18 of the indicator so that suitable advertising matter placed in the circumferential area 5 is selectively displayed at one side of the portion 18 in the various positions thereof relative to the plate member, to provide cooperation between various portions of such advertising matter. In addition, a portion 10 of the advertising matter may be applied to the portion 18 of the indicator for cooperation with the exposed portions of the area at one side of the portion 18 within the circumferential area defined by the graduations 15 19.

It is thought that the construction, operation, and advantages of this invention will be clearly understood without a more detailed description thereof. The present embodiment of the invention has been disclosed merely by way of example since in actual practice it attains the features of advantage enumerated as desirable in the statement of the invention and the above description. 20 Changes in the details of construction, and in the combination and arrangement of parts 25 may be resorted to without departing from

the spirit or scope of the invention as hereinafter claimed, or sacrificing any of its advantages.

Having thus described my invention, what I claim as new is:—

1. A novelty device of the class described including a back plate having an indenture and provided with marginal flanges formed to overhang the plate, a frame held by the flanges, a pin having one pointed end and one blunt end, an indicating member rotatable on the pin, and a transparency engaged by the flanges bearing against the blunt end 35 of the pin to hold the pointed end in the indenture. 40

2. A device of the class described including a casing, a transparency in the casing, an indicating device in the casing, means for pivotally mounting the indicating device, said indicating device merging into a triangular portion having its apices of different color, and different colored areas provided in the casing for cooperation with the 45 different colored apices. 50

In testimony whereof I affix my signature.

EDWIN G. MASTERS.
